(57) **CLAIM**

The ornamental design for a power strip as shown and described.

DESCRIPTION

FIG. 1 is a front, left and top perspective view of a power strip, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is another front, left and top perspective view of the power strip in a storage state; and,

FIG. 11 is another rear, right and bottom perspective view of the power strip in a storage state.

The broken lines depict portions of the power strip that form no part of the claimed design. The dot-dash broken lines in FIG. 1 and FIG. 9 depict the boundaries of the enlargements that form no part of the claimed design.
